UNITED STATES PATENT OFFICE.

JAMES FLEMING, OF TROY, ASSIGNOR OF ONE-HALF TO HOWARD M. DOUGREY, OF LANSINGBURG, NEW YORK.

APPARATUS FOR BRUSHING AND SHAPING SAND CORES.

SPECIFICATION forming part of Letters Patent No. 334,423, dated January 19, 1886.

Application filed October 3, 1885. Serial No. 178,881. (No model.)

To all whom it may concern:

Be it known that I, JAMES FLEMING, of 72 Federal street, in the city of Troy, county of Rensselaer, State of New York, have invented 5 a new and useful Apparatus for Brushing and Shaping Sand Cores, (Case A,) of which the following is a specification.

My invention relates to improvements in apparatus for shaping and brushing sand 10 cores, such as are used for casting interior cylindrical forms of metal, the object and purpose of my invention being to give accuracy to the measurement and adaptability of the forms used, and to facilitate their production.

15 Accompanying this specification, to form a part of it, there is a plate of drawings containing three figures illustrating my invention, with the same designation of parts by letter-reference used in all of them.

20 Of these illustrations, Figure 1 shows a side elevation of the apparatus used for brushing and turning up a sand core. Fig. 2 is a plan view of the platform on which the table that sustains the core turns. Fig. 3 is a plan view 25 of the table when turned over and with what is its under side when in position illustrated as turned toward the sight.

The several parts of the apparatus are designated by letter-reference, and the function 30 of the parts is described as follows:

The letter C designates the sand core, made in the usual way from sand and other material wet with clay-water, and which has been rammed or pressed into a cylindrical form.

35 The letter T designates the table which supports the core, and R a rack arranged on the under surface and outer edge of the said table.

The letter P designates a platform provided with rollers B', arranged in its upper surface 40 to project above it, they having proper shafts and bearings, and being arranged in said platform so that the table T may turn thereon.

The letter P' indicates a pinion arranged on the shaft S', which has its bearings b' in the 45 stud d'; and the letter D indicates a crank on the end of said pinion-shaft. This pinion is constructed to mesh into the rack of the table T, so that when the crank D is turned the said table and the core placed thereon is turned also.

50 The letter E indicates a cap constructed with an upwardly-projected vertical shaft, S²,

the latter having its bearing in an arm, A, the bottom of this cap being provided with a gage-rim, G'; and the letter G² designates a gage-rim arranged on the table T, the function of these gage-plates being to determine the diameter of the core at the top and bottom, and to furnish a bearing-line for the blade B², which is used in connection with the gage-plates, as will be hereinafter described. 55

The letters a' a² indicate arms that are pivoted at b² to the blade B², and these arms are adapted to be moved back and forth horizontally in the guideways w' of the horizontal brackets ee, that are projected from the frame F. 60 65

The letter L designates a crank arranged on the shaft M, the latter having its bearing on the bracket m', projected from the frame F.

The letter d³ indicates a lever-arm arranged on the shaft M at right angles to the crank-arm L, and O O indicate two connecting-rods, each of which is at one of its ends pivoted to the arm d³, and at their other ends they are each pivoted to one of the arms a' a². 70

The core having been pressed so that the 75 material of which it is made is cohesive, and it being arranged on the table T so as to project on its outer vertical face beyond the gage-plate G' of the table and G² of the cap, the crank D is turned and the core caused to rotate 80

by means of the engagement of the pinion P' with the rack R on the outer rim of the table T, the latter resting on the rollers B' of the platform. As the core is thus turned, the blade or templet B² is pressed against the side 85

of the core, and all that part of the latter projecting beyond the gage-plates at the top and bottom is removed, so as to finish up the core in a straight line between the gage-plates at the top and bottom, as shown at Fig. 1, when 90

such a finish is required for the outer face of the core. If, however, the core is required to have ribs turned in its outer face, the blade or templet B² may be shaped so as to turn such 95

ribs into the core as it is rotated, and the blade B² may be rounded out concavely or rounded inwardly convexly between its ends, so as to produce in the core side between the end gage-plates any concavity or convexity that may be desired, as indicated by the dotted lines d³ 100 shown in the blade-edge, and the blade may be operated to turn off the core by being forced

up against the same by means of the crank L, crank-arm d' , and connecting-rods O O, as shown, when concavity or convexity is to be imparted to the core sides; or said blade B² 5 may be held against the core side by hand when the core-lines are straight, as shown, and without concavities or convexities.

The form to be given to the core depends upon the form of the gage-plates at the top and bottom of the core, and these may be round, elliptically coincident, or made coincidentally with rectangular sides and rounded corners. When used in the latter form, the blade or templet B² is better operated by hand.

15 With an apparatus thus arranged and operated, the sand core is finished up so as to have a true surface, and the work is done rapidly and at much less cost than when done in the usual manner.

20 Having thus described my invention, what I claim, and desire to secure by Letters Patent, is—

1. In an apparatus for turning and brushing sand cores, the combination of a platform provided with rollers projected from its upper surface, a table adapted to support the core, said table being made with a circular gage-plate on its upper surface and outer edge, and a rack circumferentially arranged on its under

surface, a cap having a vertical bearing and 30 gage-plates adapted to rest on the top of the core, a pinion provided with a crank-shaft and bearing therefor, said pinion being adapted to mesh into said rack, and a finishing-blade or templet, all constructed and arranged to be 35 operated substantially as and for the purposes set forth.

2. The combination of the platform P, constructed with rollers B', the table T, made with the gage-plate G' on its outer edge and the 40 rack R on its under surface, the pinion P', arranged on the crank-shaft S', the cap C, made with the vertical shaft S' and the gage-plate G', the blade or templet B², the arms d d' , made with guideways, and the connecting-rods O O 45 and the shaft M, having bearings and provided with the crank-arm d' , said parts being connected and constructed to operate substantially in the manner as and for the purposes set forth. 50

Signed at Troy, New York, this 29th day of September, 1885, and in the presence of the two witnesses whose names are hereto written:

JAMES FLEMING.

Witnesses:

W. E. HAGAN,

CHARLES S. BRINTNALL.
